UNITED STATES PATENT OFFICE.

JESSIE M. HABERKAMP, OF CHICAGO, ILLINOIS, ASSIGNOR TO THE CHARLES E. SCOTT COMPANY, OF CHICAGO, ILLINOIS, A CORPORATION OF ILLINOIS.

NURSING BRASSIÈRE.

Application filed October 10, 1923. Serial No. 667,671.

This invention relates to bust supporting means adapted to facilitate nursing, and especially to brassières or bandeaux having breast-receiving apertures equipped with releasable closure members.

The main objects of the invention are to provide such means of improved and simplified construction; to provide a device of this sort having breast-receiving pockets and openings therefor of improved form, and having laterally swinging closure means or flaps adapted and arranged to open outward divergently from the center, and independently of each other, to expose the pockets and apertures; to provide releasable fastenings along the vertical center line of the device between the apertures to secure the flaps normally in closed position; and to provide an improved cut, form and arrangement of the pocket and flap-forming material to better accommodate the breasts and facilitate nursing.

An illustrative embodiment of this invention is shown by the accompanying drawings, in which:

Figure 1 shows a female figure with the device in place.

Fig. 2 is an enlarged front view of the device extended in substantially a flat position with the breast-flaps closed.

Fig. 3 is a similar view with the flaps open and with one of the flaps partly broken away.

In the construction shown in the drawings, the breast bandeau or brassière comprises a body part in the form of a band 1, provided with a pair of apertures 2, in combination with closure flaps 3 cut and arranged relative to the body part to form pockets 4 as shown.

The flaps 3 are of nearly rectangular shape and are sewed to the band 1 along their outer side edges 5 and partway across the top and bottom edges 5' and 5''. The inner part of each flap 3 is adapted to swing open in a horizontal direction on the fold line 6 which extends over about the middle of the corresponding aperture. When the flaps are closed their free edges 7 come together and substantially abut along the vertical center line. The said edges 7 are equipped for releasable fastening, and for this purpose are provided with button-holes 8 to receive the buttons 9 which are sewed to the body part 1 on opposite sides of and adjacent to

the vertical center line. In order to better support these buttons a reinforcing tape 10 is sewed to the back or inner side of the body part 1 and said buttons are positioned along the edges thereof, as shown by Fig. 3. 60

In order to support the device in place, shoulder straps 11 are provided as usual for brassières, and the ends of the body part are adapted for releasable fastening when brought together at the back, for which purpose mutually related hooks 12 and eyes 13 are provided on the respective ends. In order to provide for limited expansion of the device a web of elastic material 14 is inserted adjacent to one end. In order to hold the device down in front, the reinforcing member 10 is extended downwardly somewhat and provided with an adjustable terminal fastening 15 adapted to releasably engage the corset or other apparel. 75

In order to provide the best form of pockets and breast-receiving apertures, and for economic reasons, the middle part of the body member 1, constituting the inner wall of the breast covering part in which the apertures 2 are formed, is made as an insert 16 between the end sections 17 and 18. In forming this insert it is cut horizontally from the outer edges 5 to form the apertures 2 and the upper and lower sides 19 and 20 overlap as shown in Fig. 3 near their outer edges, thus providing the desired contour and pocket fullness. The flap part 3 is suitably tucked at 21 along its lower edge to provide a corresponding shape. 90

For sanitary reasons and to insure comfort, the inner wall part 16 and also the flap members 3 are formed of rubberized muslin of the highest grade.

When the device is worn the flaps are normally closed and the device is adapted to function substantially as an ordinary brassière. Whenever desired, either of the flaps may be released along the inner edge independently of the other flap, and folded back over the line 6, thus exposing the adjacent aperture, or rather the inner half of it. Owing to the pocket-like character of the double wall construction, however, this accommodates all nursing requirements, and 105 in a manner most conducive to privacy.

Although but one specific embodiment of this invention is herein shown and described, it is to be understood that numerous details of the construction shown may be altered or 110

omitted without departing from the spirit of the invention as defined by the following claim.

I claim:

- 5 A nursing bandeau the bosom part of which includes a breast receiving member formed from a single flat piece of fabric, the ends of which are deeply notched in hor-

izontal alinement, and the arms formed thereby being mutually overlapped at their outer ends, whereby said member is form-fitted to the breasts.

Signed at Chicago this 8th day of October, 1923.

JESSIE M. HABERKAMP.
